ELECTRIC CLOCK

Clinton Bateholts, Hoosick Falls, N. Y.

Application September 7, 1932, Serial No. 632,005

6 Claims. (Cl. 58—26)

This invention relates to clock mechanisms of the type in which a train of gears is driven by a synchronous motor connected to a source of alternating current, and more particularly to means for assembling such clocks.

The general object of the invention is to provide means which permits such mechanisms to be quickly and accurately assembled.

Another object of the invention is to provide means which permits such mechanisms to be so assembled as to maintain the noise incident to the operation thereof at a minimum.

For a clear understanding as to how the above and other objects are attained reference may be made to the accompanying drawing. In this drawing, however, the invention is shown merely in preferred form and by way of example, and obviously many changes and variations may be made therein and in its mode of operation which will still be comprised within its spirit. It is, therefore, to be understood that the invention is not limited to any specific form or embodiment, except insofar as such limitations are specified in the claims.

Figure 1 is a perspective view of the back supporting plate with the clock mechanism and rotor pulled away to more clearly show the assembly.

Figure 2 is a longitudinal view partially in section of the main driving shaft and associated parts.

Figure 3 is an exploded perspective view of the rotor and the clock mechanism with the bearing plates omitted, and

Figure 4 is a partial plan view of the back supporting plate showing the position of the rotor and the pole pieces.

Referring to the drawing the structure comprises three spaced bearing plates 10, 11, and 12. The plate 12 which also serves as the back supporting plate is desirably moulded from bakelite or other suitable moulding compound and has a plurality of lugs 13 extending therefrom to which the face plate of the clock is secured. The plates 10 and 11 are desirably made from sheet metal and are connected together in spaced relation by four hollow binding posts 14. As shown more clearly by Figure 1, the binding posts 14 are adapted and arranged to fit over the ends of four supporting studs 15, 16, 17, and 18 which are desirably set in place during the moulding of the back supporting plate 12. The center bearing plate 11 is held in spaced relation from the back supporting plate 12 by means of sleeves 19 and 20 which are moulded about the binding

posts 15 and 16 respectively and by metallic sleeves 21 and 22 which fit over the binding posts 17 and 18 respectively.

The synchronous motor comprises a rotor 23 and pole pieces 24 and 25. The rotor 23 is rigidly mounted on a bushing 26 which, in turn, is rigidly mounted on a main driving or rotor shaft 27, journaled in bearings 28 and 29, and the outer periphery of the rotor 23 comprises a plurality of regularly spaced radial projections 30. The pole pieces 24 and 25 are secured, as by a plurality of spun rivets 35, to two shoulder members 31 and 32 which are moulded integral with the back supporting plate 12, and the faces of the pole pieces also comprise a plurality of regularly spaced projections 33. The pole pieces are so positioned on the shoulder members 31 and 32 that the projection 33 on the pole pieces are adjacent the projections 30 on the rotor and a horizontal line *b*—*b* drawn across the top of the pole pieces is below a parallel horizontal line *a*—*a* drawn through the axis of rotation of the rotor.

A core 34 is connected across the pole pieces 24 and 25, as by a plurality of spun rivets 35a, to complete the magnetic circuit, and to prevent the occurrence of heat-creating eddy currents in the magnetic structure the armature and pole pieces are laminated. A coil 36 which is adapted and arranged to be connected to a suitable source of alternating current by conductors 37 and 38 is wound on core 34 and acts to energize the pole pieces 24 and 25 when traversed by current. The alternating current passing through the coil 36 produces a magnetic flux in core 34, the flux circuit of which is completed through the poles 24 and 25 and that portion of the rotor 23 intermediate the poles 24 and 25. This flux varies in density and direction in accordance with the current flow through the coil 36. The projections 30 on the periphery of the rotor 23 are successively attracted toward the projections 33 on the stationary pole pieces 24 and 25 after the rotor has been manually started. The operation of motors of this type is well known in the art and further explanation is not believed to be necessary. By mounting the pole pieces 24 and 25 as shown a constant downward pull is created on the rotor 23. This downward pull on the rotor maintains the rotor shaft 27 in contact with the lower portions of the bearings 28 and 29 and as a result the shaft does not have a tendency to float in the bearings. The pole pieces are preferably mounted below the rotor because when in this position the attraction ex-

erted by the pole pieces is augmented by gravity. A fly wheel 39 is loosely mounted on the bushing 26 intermediate collar 40 and a shoulder on bushing 26 to maintain uniform the rotation or rotor 23. This feature is also old in the art and further explanation is not believed to be necessary.

The bearings 28 and 29 in which the shaft 27 is journaled are preferably made from a cellulosic compound such as that sold under the trade name of Lumarith since such bearings have been found to be noiseless and to possess good wearing qualities. While a cellulosic compound is preferred as the bearing material other materials such as "Bakelite" or other suitable phenol condensation products may be used. The bearing 28 is preferably set in the back plate 12 during the moulding of the plate. It is to be understood, however, that this method of placing the bearing 28 in the plate 12 is preferred merely from a manufacturing standpoint and that the bearing may be placed in a suitable opening after plate 12 has been moulded. The bearing 29 comprises a shoulder portion which abuts the plate 11 and a hub portion 41 which extends through the plate.

As the rotor 23 rotates under the influence of the varying magnetic field it drives the main driving or rotor shaft 27. As the shaft 27 rotates it drives a sleeve 42 and a worm gear 43 fixedly mounted thereon. The worm gear 43 is in mesh with and drives a gear 44 which is fixedly mounted on one end of a shaft 45 journaled on bearings (not shown) carried by the plate 10. As the shaft 45 rotates it drives a worm gear 46 fixedly mounted thereon. The worm gear 46 is in mesh with and drives a gear 47 which is fixedly mounted on one end of a shaft 48 journaled in brackets 48a (one of which is shown) carried by the plate 11. As the shaft 48 rotates it drives a worm gear 49 which is fixedly mounted on the other end of the shaft. The worm gear 49 is in mesh with and drives a gear 50 mounted on one end of a hollow shaft 51. One end of shaft 51 is journaled on the hub portion 41 of the bushing 28 and the central portion of the shaft is journaled in bushing 52. Bushing 52 is journaled in bushing 53 which in turn is fixedly mounted in bearing plate 10. As shaft 51 rotates it drives a minute hand 54 which is secured to the other end of the shaft and a gear 55 which is fixedly secured to the central portion of the shaft behind the plate 11. The gear 55 is in mesh with and drives gear 56 which is fixedly mounted on one end of shaft 51. As shaft 51 rotates it drives a gear 58 which is fixedly secured to the other end thereof. The gear 58 is in mesh with and drives a gear 59 which is fixedly mounted on one end of the bushing 52. As the bushing 52 rotates in bushing 53 it turns the hour hand 60 which is fixedly secured to the other end thereof.

A reset gear 61 (Fig. 1) is mounted on a shaft 62 and is normally held out of mesh with gear 56 by spring 63. The shaft 62 is journaled in plates 10 and 11 and extends through an aperture 66 in the back plate 12. To permit the minute and the hour hands 54 and 60 respectively to be reset without turning the main driving or rotor shaft 27, the gear 50 is frictionally mounted on shaft 51 intermediate the spring 64 and the collar 65 (Fig. 2). To reset the hands the shaft 62 is pulled outwardly until the gear 61 is in mesh with the gear 56. The shaft 56 is then turned thereby rotating gears 56 and 58. As the gears 56 and 58 rotate they rotate gears

55 and 59 respectively. As the gears 56 and 59 rotate they drive the bushings 51 and 52 on which the minute hand 54 and the hour hand 60 are respectively mounted. The friction developed by the spring 64 against the gear 50 is insufficient to permit the gear 50 drive the worm gear 49 and as a result the gear 50 slips on shaft 51 but is sufficient to permit the worm gear 49 drive the gear 51.

An oil saturated felt washer 65 is mounted on shaft 25 adjacent the bearing 26 to lubricate the bearing during operation.

The feature of moulding the back supporting plate and providing it with a plurality of lugs on which the motor and the clock mechanism may be mounted simplifies the construction of the clock and permits the clock to be rapidly assembled without danger of the rotor shaft bearings being out of alignment.

While the pole pieces are preferably mounted so that they create a downward pull it is to be understood that favorable results may be obtained by mounting the pole pieces in other positions with respect to the rotor. For example the pole pieces may be mounted so as to create a constant upward pull or a constant side pull on the rotor. The essential feature in all cases being that the pole pieces shall be mounted on one side of a straight line drawn through the axis of rotation so as to create a steady pull on one side of the outer periphery of the rotor.

I claim:

1. In an electric clock having a gear train assembled in a frame, a moulded back supporting plate having lugs extending therefrom for supporting said frame, a main drive shaft for driving said train, one end of said shaft being journaled in said back supporting plate, and the other end of said shaft being journaled in said frame and electro-magnetic means for rotating said shaft.

2. In an electric clock having a gear train assembled in a frame, the combination of a back supporting plate having lugs extending therefrom for supporting said frame, a main drive shaft for driving said train, one end of said shaft being journaled in said plate and the other end of said shaft being journaled in said frame, a rotor mounted on said shaft and magnetic pole pieces secured directly to said plate adjacent the outer periphery of said rotor.

3. In an electric clock having a gear train assembled in a frame, the combination of a back supporting plate having lugs extending therefrom for supporting said gear frame, a main drive shaft for driving said train, one end of said shaft being journaled in said plate and the other end of said shaft being journaled in said frame, a rotor mounted on said shaft and magnetic pole pieces secured directly to said plate adjacent the outer periphery of said rotor and on one side of a straight line drawn through the axis of rotation of said rotor.

4. In an electric clock having a gear train assembled in a frame, a back supporting plate having lugs extending therefrom for supporting said frame, a non-metallic bearing carried by said plate, a non-metallic bearing carried by said frame, a main shaft journaled in said bearings and adapted to drive said train and means responsive to an electrical impulse for rotating said shaft.

5. In an electric clock having a gear train assembled in a frame, a back supporting plate having lugs extending therefrom for supporting said

frame, a non-metallic bearing carried by said plate, a non-metallic bearing carried by said frame, a main shaft journaled in said bearings and adapted to drive said train, a rotor mounted on said shaft and means responsive to an electrical impulse for rotating said rotor to drive said shaft.

5. In an electric clock having a gear train assembled in a frame, pole pieces, a back support-

ing plate having lugs extending therefrom for supporting said frame and shoulders extending therefrom for supporting said pole pieces, a non-metallic bearing carried by said plate, a non-metallic bearing carried by said frame, a main shaft journaled in said bearings and adapted to drive said train, and a rotor mounted on said shaft adjacent said pole pieces.
